PROCESS OF TREATING OR FORMING AN INSOLUBLE PLUTONIUM PRECIPITATE IN THE PRESENCE OF AN ORGANIC SURFACE ACTIVE AGENT

Joseph H. Balthis, Wilmington, Del., assignor to the United States of America as represented by the United States Atomic Energy Commission

Filed Dec. 29, 1944, Ser. No. 570,419

4 Claims. (Cl. 23—14.5)

This invention relates to a procedure for processing of materials containing the element of atomic number 94, known as plutonium, for separating the plutonium from extraneous matter such as substances of the kind present in neutron irradiated uranium exemplified by uranium and especially fission products, and the like radioactive contaminants. More particularly, this invention concerns a separatory and concentration procedure involving the use of a fluoride type of carrier wherein certain improved procedure is employed in forming the carrier.

As described herein, the isotope of element 94 having a mass of 239 is referred to as 94^{239} and is also called plutonium, symbol Pu. In addition, the isotope of element 93 having a mass of 239 is referred to as 93^{239} . Reference herein to any of the elements is to be understood as denoting the element generically, whether in its free state or in the form of a compound, unless indicated otherwise by the context.

Elements 93 and 94 may be obtained from uranium by various processes which do not form a part of the present invention including irradiation of uranium with neutrons from any suitable neutron source, but preferably the neutrons used are obtained from a chain reaction of neutrons with uranium.

Naturally occurring uranium contains a major portion of $_{92}\text{U}^{238}$, a minor portion of $_{92}\text{U}^{235}$, and small amounts of other substances such as UX_1 and UX_2 . When a mass of such uranium is subjected to neutron irradiation, particularly with neutrons of resonance or thermal energies, $_{92}\text{U}^{238}$ by capture of a neutron becomes $_{92}\text{U}^{239}$ which has a half life of about 23 minutes and by beta decay becomes 93^{239} . The 93^{239} has a half life of about 2.3 days and by beta decay becomes 94^{239} . Thus, neutron irradiated uranium contains both 93^{239} and 94^{239} but by storing such irradiated uranium for a suitable period of time, the 93^{239} is converted almost entirely to 94^{239} .

In addition to the above-mentioned reaction, the reaction of neutrons with fissionable nuclei such as the nucleus of U^{235} results in the production of a large number of radioactive fission products. As it is undesirable to produce a large concentration of these fission products which must, in view of their radioactivity, be separated from the 94^{239} and further as the weight of radioactive fission products present in neutron irradiated uranium is proportional to the amounts of 93^{239} and 94^{239} formed therein, it is preferable to discontinue the irradiation of the uranium by neutrons when the combined amount of 93^{239} is equal to approximately 0.02 percent by weight of the uranium mass. At this concentration of these substances, the concentration of fission elements which must be removed is approximately the same percentage.

A number of processes have already been proposed for accomplishing the separation and concentration of Pu. Certain of these processes are generically known as the "bismuth phosphate" type process and the "wet fluoride" type of process. These processes are the invention of others and the details of the processes are described in copending applications as for example application Ser.

2

No. 519,714, now U.S. Patent No. 2,785,951, issued March 3, 1957, to be referred to hereinafter, which gives details relative to such processes. Consequently, all of the details of operation of the aforementioned processes are not described herein.

In some instances, it has been customary to utilize in the same separation and recovery process both the bismuth phosphate treatment and lanthanum fluoride treatment. The present invention in its preferred embodiment concerns the formation of the fluoride type of precipitates exemplified by a lanthanum fluoride precipitate carrying Pu. In processes of the aforementioned type, either combination processes where several different types of carriers are used, including the formation of a fluoride precipitate, or processes where fluoride compounds are more or less directly precipitated, the formation of these fluoride compounds carrying Pu or fission products or comprising a fluoride compound of Pu may present certain difficulties. For example, one carrier precipitate commonly formed is lanthanum fluoride. This precipitate has been formed under acid conditions by adding to the acid solution a source of fluoride ions and a source of lanthanum ions. The characteristics of the precipitates formed are such as to present some difficulty of separation because of the finely divided nature and dispersion thereof. That is, it has been required to centrifuge these precipitates at relatively high speeds for extended periods or to employ a special filtration technique for separation from the surrounding liquid. It has also been required to precipitate the LaF_3 in two portions, separating after each precipitation.

In accordance with the present invention, it has been found that a precipitate of better characteristics may be formed by the use of surface active agents either alone or in conjunction with certain other modifications of precipitation conditions.

The meaning of the terms bismuth phosphate type of process, fluoride type of process, product and by-product precipitate, coformed, preformed, and similar terms will be apparent as the description proceeds.

The invention has for one object, to provide improvements in methods for the separation and recovery of plutonium.

Another object is to provide a method of separating plutonium by procedure wherein certain additions different from those heretofore used are employed.

Another object is to provide improved procedures for forming certain precipitates.

Still another object is to provide a new procedure particularly useful in forming a fluoride carrier precipitate containing Pu.

Another object is to provide a new procedure for forming by-product fluoride carrier precipitates.

Still another object is to provide a procedure for forming fluoride carrier precipitates which exhibit improved characteristics.

Another and particularly important object is to improve the centrifuging characteristics of lanthanum fluoride precipitates.

Still another object is to provide a type of process which lends itself to combination with steps already known or practiced.

Another object is to provide a type of process which may employ the materials used in existing processes, but under different conditions, and which may be carried out in existing equipment without change, or with a minimum of equipment change.

Still another object is to provide treatments for fluoride precipitates which do not exert a detrimental effect on subsequent process steps to which the precipitates may usually be subjected.

Other objects will appear hereinafter.

I have found that Pu in admixture with various extraneous material may be separated and concentrated by the use of the series of steps involving the formation of certain carrier precipitates. These treatments may be generally similar to known practice as respects reagents, temperatures and similar features. However, I have found that the formation of such carrier precipitates may be rendered simpler and more efficient by modification of precipitation conditions, the use of surface active agents and other features as will be described in detail hereinafter. By the formation of the carrier precipitate under the conditions of the present invention, not only are the advantages previously obtained in the processes still obtainable, but there are also obtained advantages such as the production of precipitates having improved centrifuging characteristics.

Illustrations of some of the types of carrier precipitates which may be improved by the present invention are described in application Ser. No. 519,714, filed January 26, 1944, Thompson and Seaborg, and reference is made to that application for further disclosure, details thereof being omitted from the present disclosure except where necessary to an understanding of the present invention. As set forth in said application, it has been discovered that plutonium has more than one oxidation state, including a lower oxidation state or states referred to herein as $Pu^{(r)}$ in which the element is characterized by forming insoluble phosphates and fluorides and a higher oxidation state or states referred to as $Pu^{(o)}$ in which the element forms soluble phosphates and fluorides.

In accordance with the present invention, for example, a fluoride type carrier precipitate such as a LaF_3 precipitate as described in the aforementioned application would be formed by procedure involving the use of a surface active agent such as Aresklene or the like.

The solutions containing Pu which may be treated, and in which the fluoride precipitate may be formed by my invention are the same type of solutions as heretofore treated. A common type of solution containing Pu subject to separation and recovery procedures is a solution which has been initially processed by the bismuth phosphate type of treatment. Such type of solution and its treatment are described in detail in application Ser. No. 519,714 aforementioned. These solutions comprise a nitric acid containing liquid having a content of Pu therein. The nitric acid solution may also contain other acids such as a content of phosphoric acid and oxalic acid. The solution may also contain certain extraneous matter such as radioactive materials which the subsequently applied fluoride precipitation treatments may eliminate or reduce. As indicated above, by means of a fluoride precipitation treatment applied to the solution containing the Pu in the reduced (r) condition, the resultant fluoride precipitate (product precipitate) carries the Pu away from extraneous matter. By means of a fluoride precipitation applied to the solution having the Pu in the oxidized (o) state (by-product precipitate), extraneous matter is carried away by the fluoride precipitate leaving the $Pu^{(o)}$ in the supernatant liquid from this precipitation.

The formation of fluoride precipitates exemplified by lanthanum fluoride carrier precipitates may be accomplished in several different ways. A preformed precipitate is produced by incorporating a source of an excess of fluoride ions such as excess hydrogen fluoride into the solution containing Pu in which the carrier precipitate is to be formed. Thereafter a source of lanthanum ions is added to the process solution. In other words, a preformed precipitate is produced by procedure described as a lanthanum strike.

A coformed precipitate is produced by operation de-

scribed as a hydrogen fluoride strike. That is, the source of lanthanum ions is first incorporated in the solution in which the carrier is to be formed, thereafter the hydrogen fluoride is added to cause the formation of the lanthanum fluoride precipitate.

Broadly, therefore, my invention may be applied to various type solutions in which the precipitates may be formed in various ways. The solutions to be processed by my invention preferably have added thereto one or more surface active agents as may be required at substantially any time during the process dependent upon the particular composition and condition of the solution and the nature of the agent added.

For a further understanding of my invention and appreciation of some of the advantages of the invention in improving the characteristics of the precipitates obtainable, by the incorporation of surface active agents, a number of examples are set forth hereinafter. In general, for the purposes of comparison some runs are described in

connection with the examples as carried out for the purposes of control. That is, some of the runs were carried out under various conditions as will be discussed but without the use of surface active agents in the process. It will be noted that some improvement in the precipitate characteristics may be obtained by the control of certain conditions as will be discussed. Then examples were carried out in a manner substantially exactly the same as the particular control run but with the addition of surface active agents in accordance with the present invention.

In order to make a more definite comparison, tests were made on slurries for determining the rate of settling and sedimentation volume. This was determined by pouring slurry (carrier precipitate plus surrounding liquid) into graduated 100 cc. tapered glass tubes and recording

the volume of sediment as a function of the time. By comparative tests with the controls and the runs comprising surface active agents an indication of the improvement obtainable by employing a particular feature of the invention is given.

Another measurement which may be made is referred to herein as the centrifugation improvement factor. This is the ratio of centrifugable product in the supernatant from untreated precipitate (control) to that in the supernatant from treated precipitates (precipitates in which agents in accordance with the present invention have been incorporated). The slurries under such comparison are centrifuged substantially identically.

In further detail, this may be accomplished by pipetting, for example, one cc. samples from each of the mechanically stirred slurries to be compared, transferring to 3 cc. glass tubes constricted at the bottom to retain solids while pouring off the bulk of the supernatant. These samples are simultaneously centrifuged in these tubes under carefully controlled conditions (for example one

minute at 220 G) followed by immediately pouring off the supernatants into 50 cc. containers. The product content of the supernatants may be determined by measuring their alpha activity.

The term relative centrifugal force (RCF) as used herein is conventional and refers to the maximum obtained. In the runs described the time indicated for centrifugation includes that required to reach the desired r.p.m. but does not include the time of coasting to a stop. As will be observed as the description proceeds,

in large scale continuous centrifuges a relative centrifugal force of greater than 1500 G is usually applied in order to cause satisfactory separation of the fluoride carrier precipitate. On the other hand, when fluoride precipitates are formed employing procedure in accordance with the present invention, a force of even below 500 G is in many instances ample to obtain satisfactory centrifugation.

An additional understanding of this aspect that prior procedure has required high speed centrifuging may be

had by reference to the following table of data covering continuous centrifugation operations:

HF normality	Centrifuge, r.p.m.	Relative centrifugal force (G)	Average time in centrifuge bowl (minutes)	Percent of original Pu in centrifuge effluent
1.0.....	1,740	1,700	8	4.55
1.0.....	1,740	1,700	8	4.6
1.0.....	870	420	8	15.0
0.5.....	1,740	1,700	8	8.3

In producing the fluoride precipitates described as centrifuged in the preceding table, oxalic acid reduced solution was made of the normality in HF indicated. There was then added a quantity of lanthanum ammonium nitrate solution to give a concentration equivalent to about 125 milligrams of La^{+3} per liter. This was added at about 3% per minute. The slurries (lanthanum fluoride precipitates plus supernatant liquor) were digested at between 25° C. and 32° C. and then subjected to centrifuging. As may be observed from the table, when centrifuge speeds of greater than 1700 r.p.m. were employed, only about 4½% of the Pu was retained in the precipitate remaining unseparated. When the centrifuge speed was reduced to about one-half, namely, when an r.p.m. of about 870 was used the loss increased to about 15%.

It is therefore apparent from the foregoing that fluoride precipitates when prepared in a conventional manner have required relatively high centrifuging speeds to obtain reasonably satisfactory separation.

It has been found that the centrifuging characteristics of such lanthanum fluoride precipitates may be improved somewhat by subjecting them to vigorous agitation during formation. In general under normal conditions lanthanum fluoride precipitate remains partially suspended in aqueous medium for one-half to three hours when agitation is interrupted. When the precipitate has been preformed, the almost transparent precipitate flocculates after several minutes and settles to a relatively large volume of gelatinous sediment. Coformed lanthanum fluoride is more opaque and settles more slowly to a smaller volume of less flocculent sediment.

As indicated, it has been found that the degree of agitation during the formation of such precipitates affects the centrifuging characteristics of both preformed and coformed lanthanum fluoride. The ease of centrifugation for the precipitates obtained increases with the rate of agitation employed during their process of formation. In carrying out these runs where agitation was applied, identical paddle agitators were used. The preferred agitation under the particular circumstances involved the use of a baffled tank with the agitator revolving at 220 r.p.h. However, other rates of agitation may be used.

Both the preformed and coformed lanthanum fluoride precipitates were prepared by using 125 milligrams per liter of La^{+3} and 0.5 N HF. The precipitates were digested for one hour. The solutions treated and in which the precipitates were formed were standard oxalic acid reduced solutions.

The effect of the agitation in improving centrifugability is indicated in the next table.

PERCENT OF ORIGINAL PU IN SUPERNATANT AFTER CENTRIFUGATION AT SPECIFIED CONDITIONS

RCF, G	Slow agitation, percent	Moderate agitation, percent	Rapid agitation, percent
45.....	49.75	20.75	15.9
118.....	34.5	11.5	5.55
210.....	11.1	6.55	2.15
340.....	10.3	4.8	2.15
520.....	8.35	2.65	1.25
730.....	3.8	1.4	0.75
1,010.....	2.1	1.2	0.5

I have found that, in general, by adding surface active agents in processes of forming precipitates of the class described, the characteristics of the resultant precipitates may thereby be substantially improved. The settling rates of such precipitates and other characteristics are improved yet at the same time the ability of the precipitates to carry Pu in the event the Pu is in a reduced condition, or to carry by-products in the event oxidizing conditions are present, is not impaired. That is, a precipitate of the class described prepared by the best procedure available including such modifications as employing rapid agitation during formation of the precipitate, may be further improved by the utilization of surface active agents in accordance with the present invention.

- 10 The agents which may be used may be cationactive, anionactive, or non-ionic. As is known, there are an extremely large number of such agents available commercially. In the practice of the present invention it is possible to use commercially obtainable agents. Consequently, for convenience and practicability of description, reference will be made herein to the commercial name under which some of these agents are known. No attempt is made herein to enumerate all possible agents. Likewise, the invention is not to be regarded as limited 25 as respects an agent manufactured by some particular method.

One agent which has been found to be quite satisfactory is Areskrene 400. This material is commercially obtainable and is stated to be a dibutyl-phenyl-phenol 30 sodium disulfonate. Another agent which has been found to be quite useful is Neomerpin N. Likewise, this is a commercially obtainable compound stated to be an alkyl naphthalene sulfonic acid.

Many other surface active agents are described in Industrial and Engineering Chemistry, Industrial edition, for January 1941, and in a number of other publications. Still another agent which has been found to give good 35 results when used in the present invention is lecithin. The commonly available commercial products are obtained from soy beans and contain soya oil, free fatty acids and phosphatides. Soya lecithin is available in several different grades. For example Lipoidol is a low cost technical grade. Yelkin C is a commercial product 40 stated to be a water dispersable grade of soya lecithin containing Carbitol (diethylene glycol monoethyl ether).

45 For the purposes of illustrating some of the specific embodiments of my invention, reference is made to the following examples.

Example I

50 In this example the species of agent added was soya lecithin. Under this example a number of runs were carried out as will be described wherein the agent was present during and after the formation of the precipitate. 55 Also in the various different runs, different quantities of agent were added.

Run (a) was a control run. The starting solution was standard oxalic acid reduced nitric acid solution of the type already described. The solution contained Pu and 60 had been subjected to prior bismuth phosphate treatment. The solution was in a condition to be subjected to a lanthanum fluoride carrier precipitation treatment for carrying down the Pu.

A 100 ml. sample of this solution was used for the 65 control. The lanthanum fluoride carrier precipitate was formed therein by an HF strike. That is, approximately 10.4 ml. of a source of lanthanum ions (La^{+3}) were incorporated into the solution. This source contained 2.5 mg. of La^{+3} per ml. Thereafter there was added 4.1 70 ml. of concentrated HF incorporated at the rate of 3% per minute. The resultant precipitate was digested for 1½ hours at room temperature. The slurry was poured into a 100 ml. tapered glass tube of the type already described under settling and sedimentation tests and permitted to settle. The observed settling as a function of

time, was noted and the data plotted as will be referred to in connection with FIG. 1 of the attached drawing forming a part of the present application.

Run (b) was carried out substantially the same as the preceding run excepting that there was present during the precipitate formation a content of soya lecithin. The amount added was approximately 22% weight based on the weight of lanthanum. Likewise in this run after digestion of the precipitate the slurry was poured into a 100 cc. bottle and the settling observed, the data being recorded as illustrated in FIG. 1.

Run (c) was carried out substantially identical with the preceding runs excepting that in this run the quantity of soya lecithin agent incorporated was 50%. This was incorporated before precipitation, and consequently was present during the precipitate formation. The settling data with respect to this run was recorded as indicated in FIG. 1.

Run (d) was likewise similar to the preceding methods excepting that 22% soya lecithin was added after the lanthanum fluoride precipitate had formed. In other words, the primary difference in this run over run (b) was merely the point or time of addition in the process, namely after the lanthanum fluoride precipitate had formed. The settling rate was observed and the data recorded as illustration in FIG. 1.

Run (e) likewise was generally similar to the preceding runs excepting that in this run 40% lecithin was added after the precipitate had formed. The settling rate was noted and recorded as illustrated in FIG. 1.

Referring now to FIG. 1 of the drawing, by reference to the control and comparison of this curve with the other curves, it will be observed that the addition of the agent either before or after precipitate formation improves the settling rate. It may be further noted that in the case of the particular agent under description, and the other conditions of the runs, that the addition of the agent after the precipitate formation gave a greater improvement in the settling rate. While this is significant with respect to the particular example described, it is desired to point out that in the instance of some agents, the greatest improvement may be obtained by having the agent present during the precipitate formation. In general, however, in all instances whether the agents be added before, during, or after precipitation, improvement may be obtained. Hence, it is not desired to limit the present invention as respects the exact time and point of agent addition.

Example II

In this example the species of agent added to improve the fluoride carrier precipitate was agar-agar. This is a well known and readily available material, consequently, further description thereof is not required. Likewise, in this example a number of runs were carried out wherein various amounts of the agar were incorporated under a variety of conditions. However, for the purposes of this example it appears satisfactory to describe merely a few of these runs illustrative of the action thereof.

Run (f) constituted the control run. 100 ml. of starting solution was employed for the control. This starting solution comprised an oxalic acid reduced nitric acid solution containing Pu which had been freed of at least a part of its contamination by preliminary treatments. There was incorporated into the solution approximately 10 ml. of solution containing 2.5 mg. of La^{+3} per ml. Thereafter there was incorporated 0.8 ml. of concentrated HF added at the rate of 3% per minute. The resultant slurry was digested in a conventional manner and poured into a container for observing the settling in the manner comparable to that already described. The settling of the control was observed and the data plotted as illustrated in FIG. 2.

Run (g) was exactly similar to the preceding run excepting that the solution was made approximately 1% in

agar before forming the precipitate. That is, approximately 1.25 ml. of a 0.02 percent agar solution was added so that the agar would be present during the formation of the lanthanum fluoride precipitate. After digesting in 5 a manner comparable to the control, the slurry was poured into the graduated container for observing the settling rate. The data concerning this run is recorded in FIG. 2.

Run (h) was similar to the preceding examples excepting that the solution was made 10% in agar prior to precipitation. That is, approximately 12.5 ml. of the agar solution was incorporated. After precipitate formation and digestion, the slurry was poured into a container for observing the settling. The data on this run is recorded 15 in FIG. 2.

A number of other runs were carried out wherein other concentrations of agar were tried. Since the data observed is to a large extent merely cumulative, inclusion herein is considered unnecessary.

20 Referring to FIG. 2, it will be noted that the incorporation of even the 1% agar improved the settling. The incorporation of the 10% of an agent still further increased the settling rate. The agar addition caused the rapid settling of the precipitate into a slimy floc somewhat on the luminous side. The supernatants from the processes in which agar was used were not as clear as supernatants from operations where other agents were used. For example, as will be described, Aresklenne not only gives rapid settling, but the resultant supernatant 30 very quickly becomes completely clear.

Example III

In this species the agent used was Aresklenne. Likewise under this example a number of runs were carried 35 out for preparing both preformed and coformed precipitates. In addition the variation was made in the process of permitting the slurries to undergo a period of quiescence prior to centrifuging. In all of the runs described in this example, the lanthanum fluoride precipitate was 40 formed by using a concentration of La^{+3} of 125 mg. per liter. The concentration of hydrogen fluoride was 0.5 N. The type of solution treated was oxalic acid reduced nitric acid solution containing Pu of the type as already described.

45 Certain data noted in respect to the several runs, is set forth in the table which follows, relative to the percent of product in supernatant after one minute of centrifugation at 220 G.

50	Quiescent period before centrifuging, minutes	Type of precipitate			
		Control (preformed, no flocculant), percent	Control (coformed, no flocculant), percent	Preformed, 20% by weight of Aresklenne, percent	Coformed, 20% by weight of Aresklenne, percent
55	2.....	6.4	4.9	3.4	2.1
	5.....	6.8	4.2	6.0	2.6
	10.....	4.6	4.3	4.5	1.9

60 It will be observed from the data set forth in the table that the percentage of product remaining in the supernatant in the runs where the agent had been included was much smaller than in the control runs. This signifies that 65 the addition of the agents permitted the centrifuging out of a much larger quantity of product in the one minute centrifugation at 220 G. As indicated, a number of runs were conducted and the results averaged, this information being recorded as illustrated in FIG. 3. It will be 70 observed that under the same circumstances the centrifugation loss when an agent is present may be considerably less than half as may be noted by comparison with the control.

A large number of other examples have been carried out 75 along the same general lines as have been described in

detail above. In these examples various agents have been incorporated at various stages in the process of forming both preformed and coformed precipitates. Likewise the liquids treated were of usual types. For convenience of consideration, the information respecting these further examples is summarized below in the following table

IMPROVEMENT IN CENTRIFUGABILITY ACHIEVED BY SURFACE ACTIVE AGENTS

AGENTS ADDED BEFORE PRECIPITATION OF LaF_3

Example No.	Type of precipitate	Flocculating agent	mg./l. of La^{+3}	HF normality	Centrifugation improvement factor
IV	Coformed	20% Aresklene	125	0.5	8.0
V	do	20% Neomerpin N	125	0.5	4.0
VI	do	50% Fixanol	125	0.5	1.0
VII	Prefomed	20% Aresklene	125	0.5	1.6
VIII	do	20% Neomerpin N	125	0.5	2.4

AGENTS ADDED AFTER PRECIPITATION AND ONE HOUR DIGESTION OF LaF_3

IX	Coformed	20% Aresklene	125	1.0	4.3
X	do	20% Yelkin C	125	1.0	3.0
XI	do	20% Aresklene	125	0.5	4.3
XII	do	20% Yelkin C	125	0.5	3.2
XIII	do	20% Neomerpin N	125	0.5	5.0
XIV	Prefomed	20% Aresklene	125	1.0	2.2
XV	do	do	125	0.5	1.2
XVI	Coformed	do	225	0.5	3.9
XVII	do	do	125	0.5	3.7
XVIII	Prefomed	do	225	0.5	1.4
XIX	do	do	125	0.5	1.6

As indicated above, the operation of the invention is not limited to a specific type agent. Satisfactory results have been obtained with anion-active, cation-active, and non-ionic agents. Information illustrating these different groups is set forth in the table set forth below. All of the agents added produced substantially improved results.

Classification of agents	Agent present during LaF_3 precipitation (testing method: Add agent to solution, coform LaF_3 in 0.2 N HF, compare rate of settling and sediment volume to that of an untreated control)	Agent added after LaF_3 precipitation (testing method: Coform LaF_3 in 0.2 N HF, add agent, compare rate of settling and sediment volume to that of untreated control)
Anion-active	Aresklene 400—rapidly settling flocs. Agar—rapid settling of flocs occupying a large volume. Duponol G—larger sediment volume.	Neomerpin N. Aresklene 400.
Cation-active	Fixanol—rapid settling at high concentration of agent. Sapamine KW—rapid settling at high concentration of agent.	Duponol G. Duponol ME. Agar.
Non-ionic	Tergitol Penetrant 04—some coagulation.	Soya lecithin (Yelkin C).

Example XX

In this example soya lecithin was added in a manner the same as described, in three runs, using a centrifuge having a 12" bowl, to flocculate the LaF_3 -product precipitate produced by precipitation in 0.2 N HF. Two of the treated precipitates (slurries) were centrifuged at 410 G, the other at 1510 G. Product losses in the centrifuge effluents were normal (1.9%, 1.3%, and 0.6%). It is apparent from the foregoing that by the use of the present invention it was possible to run the centrifuge at about one-third of the usual speed and obtain a separation substantially as good and in some instances better than in prior conventional operations. The separated precipitate was then solubilized by metathesizing to lanthanum-plutonium hydroxides by treatment with aqueous KOH. Metathesis waste losses were normal. A nitric acid solu-

tion of the metathesized product behaved satisfactorily in a concentration cycle thereafter carried out.

Example XXI

An aqueous nitric acid solution containing oxidized plutonium and radioactive fission products was provided with sufficient bismuth in the form of nitrate to yield in the final mixture a bismuth concentration of 2½ grams per liter. Sufficient phosphoric acid solution was added to provide a 0.1 molar H_3PO_4 solution upon precipitation of the bismuth as bismuth phosphate. The mixture was digested for one hour at 75° C., then an amount of Neomerpin N equal to 20% by weight of the bismuth present was added and the mixture was digested for an additional half hour during which the solution cooled to room temperature. The mixture was then centrifuged to separate the bismuth phosphate precipitate and radioactive fission products. After the separation, the solution contained less than one-half as much residual fission products as contained in similar solution formed in a control test omitting the surface active agent but carried out under otherwise similar conditions.

Example XXII

A solution containing oxidized plutonium and radioactive fission products was treated with sufficient hydrogen fluoride solution to provide a final concentration of 0.2 N HF after precipitation. Sufficient lanthanum was added as a 1% HNO_3 solution of lanthanum ammonium nitrate to provide 125 mg. of lanthanum per liter of solution. The mixture was digested at room temperature for ½ hour with agitation. 20% by weight of Aresklene, based on the weight of lanthanum present, was then added and the mixture was digested for one hour more at room temperature. It was then centrifuged to separate solid matter. The centrifuging time for removing the precipitate was approximately one-fourth the time required for a corresponding separation in a control test under similar conditions but omitting the surface active agent.

The use of an alkyl-aryl alkali metal sulfonate, exemplified by Aresklene, is preferred. However, various other agents also give materially improved results such as the use of Neomerpin N and soya lecithin. In general, under average conditions around 15-30% by weight of the agent based on the weight of lanthanum is a satisfactory quantity to use either singularly or in the aggregate in the event more than one agent is used. However, amounts from 1% to 200% have been tested and found to give improved results. In processes of the present type where it is desired to obtain concentration, and it is desired to keep quantities to a minimum, the use of excess is preferably avoided but is not precluded. The use of large excesses might carry over into succeeding steps and require added steps for effecting their removal. In some instances, the improvement obtainable by the use of agents in accordance with the present invention may be taken advantage of to permit reduction in the number of precipitations and centrifugations required for satisfactorily recovering all of the valuable component contained in the solution being treated.

In general, one of the advantages obtainable by the use of the present invention is to permit the obtaining of satisfactory separation by using lower centrifuging speeds. This is illustrated by the ability, by the use of the present invention, to reduce the centrifugation speed of around 1700 G heretofore used in processes of the class described to about 420 G and still obtain satisfactory separation.

While in a number of the examples the preferred operation has been to incorporate the agents after the formation of the precipitate, the invention is not limited in this respect. It is, however, generally preferred to employ La^{+3} strike and follow this operation by the addition of the agent. When using Aresklene, however, it has been

noted that maximum improvement is usually obtained by an HF strike in the presence of the agent.

The use of agents in accordance with the present invention in processes for recovering the valuable product, Pu, apparently does not adversely affect existing procedures to which the invention may be applied. That is, the addition of the agents does not strip the Pu from lanthanum fluoride carrier precipitates, and apparently does not inhibit the carrying of the Pu under process conditions. In instances where small quantities of the agents may be carried through the subsequent steps of the process by the carrier precipitate as, for example, through the metathesis into the solution of metathesized product, this residuum apparently does not interfere with the oxidation of Pu and has no adverse effect upon subsequent concentration cycles which may be applied for concentrating or segregating Pu.

While my invention has been described as employed in preparing the fluoride type of precipitate, illustrated by lanthanum fluoride, since this constitutes the preferred embodiment as well as a type of precipitate frequently encountered in plant processes, my invention is not limited thereto. Similar procedure may be applied in the formation of other precipitates exemplified by the formation of potassium plutonium fluoride and plutonium peroxide precipitates or to BiPO_4 , CeF_3 , or other carrier precipitates containing Pu. In certain other instances precipitates which do not flocculate or otherwise present difficulties of formation and separation may be improved by the application of the principles of my invention; for example, radioactive fission elements may be more completely separated with a BiPO_4 by-product precipitate when a surface active agent is used, or the agents may also be used to flocculate LaF_3 by-product precipitates.

The process may be applied to solutions containing Pu from tracer amounts to several hundred milligrams per liter. The concentration of La^{+3} ion may be from about 50 to 300 mg. per liter, added in several additions if desired. The concentration of HF may be within the range of about 0.2 to 2 N. While HF has been referred to as the source of fluoride ions, other reagents such as NaF , KF , and the like may be used. Such details are described in other copending applications and form no part of the present invention excepting that in the present invention it has been possible in many instances to use lower concentrations and obtain satisfactory results. However, my invention is not limited in these respects as the concentrations of the reagents suggested are merely guides to preferred practice. Likewise, metathesis refers to an operation customarily employed in processes of the pres-

ent type and involves the use of alkali metal hydroxides and/or carbonates in a process of converting fluoride precipitates to acid solutions thereof. Since such processes are described in detail in other applications, description herein is unnecessary.

It is to be understood that all matter contained in the above description and examples shall be interpreted as illustrative and not limitative of the scope of this invention, and it is intended to claim the present invention as broadly as possible in view of the prior art.

I claim:

1. In a process for the separation of plutonium from a solution containing a compound of plutonium and compounds of other elements, in which an insoluble precipitate is formed in said solution and the precipitate together with its associated plutonium is thereafter separated from the supernatant solution, the improvement which comprises subjecting said precipitate to the action of dibutyl-phenylphenol sodium sulfonate prior to separating said precipitate from said supernatant solution.
- 15 2. In a process for the separation of plutonium from a solution containing a compound of plutonium and compounds of other elements, in which an insoluble precipitate is formed in said solution and the precipitate together with its associated plutonium is thereafter separated from the supernatant solution, the improvement which comprises subjecting said precipitate to the action of dibutyl-phenylphenol sodium sulfonate.
- 20 3. In a process in which lanthanum fluoride is precipitated in an aqueous solution and thereafter separated from the supernatant solution, the improvement which comprises subjecting said precipitate to the action of dibutyl-phenylphenol sodium sulfonate.
- 30 4. In a process in which bismuth phosphate is precipitated in an aqueous solution and thereafter separated from the supernatant solution, the improvement which comprises subjecting said precipitate to the action of dibutyl-phenylphenol sodium sulfonate.
- 35 5. In a process in which lanthanum fluoride is precipitated in an aqueous solution and thereafter separated from the supernatant solution, the improvement which comprises subjecting said precipitate to the action of dibutyl-phenylphenol sodium sulfonate.
